UNITED STATES PATENT OFFICE.

ARTHUR DUFFY, OF IVANHOE, AND CHARLES J. RELING, OF CINCINNATI,
OHIO; SAID RELING ASSIGNOR, BY MESNE ASSIGNMENTS, TO MILLER
OUTCALT, OF CINCINNATI, OHIO.

CRADLE.

SPECIFICATION forming part of Letters Patent No. 378,389, dated February 21, 1888.

Application filed July 15, 1887. Serial No. 244,404. (No model.)

To all whom it may concern:

Be it known that we, ARTHUR DUFFY and CHARLES J. RELING, both citizens of the United States, the former residing at Ivanhoe, in the county of Hamilton and State of Ohio, and the latter at Cincinnati, in the same county and State, have jointly invented certain new and useful Improvements in Cradles, of which the following is a full, clear, and exact description, reference being had to the accompanying drawings, forming part of this specification.

Our invention relates to that class of rocking cradles which are provided with platforms, and has for its object the application to such cradles of novel fan mechanism, whereby the rocking of the cradle actuates the fan.

The novelty of our invention will be herein set forth, and specifically pointed out in the claims.

20 In the accompanying drawings, Figure 1 is an end elevation of a cradle, showing the application of our invention. Fig. 2 is a side elevation of the same.

The same letters of reference are used to indicate identical parts in both figures.

25 A represents any ordinary cradle, whose rockers B rest upon a platform C, of the usual or any suitable construction.

D is an upright rod secured at its lower end to the platform C. This rod may be made adjustable, if desired, by means of the set-screw h, as shown. Its upper end is coiled, as at a, bent over and downward, as at b, and formed into an eye, as at c, to form bearings for a horizontal fan-shaft, E, which is inserted through the eye c and loop a, and has secured to it between these bearings a grooved pulley, F. The fan-shaft E is preferably extended to near the foot of the cradle, and has adjustably attached to it, by means of the eye-piece d and set-screw e, any suitable fan, G. A cord, H, is passed over the pulley F and extends down around a second double-grooved pulley, I, upon a stud, f, secured to the rod D, and has its ends secured to the rocker of the cradle at each side,

as shown in Fig. 1. One or both of the ends of the cord may be connected to the rockers by spiral springs g. It results from this construction that when the cradle is rocked the shaft E will be oscillated and the fan vibrated, as 50 will be readily understood.

By means of the eye d and set-screw e the fan may be adjusted along the shaft E, as desired.

When not in use, the fan-shaft E may be turned to throw the fan up out of the way, as 55 indicated by the dotted lines in Fig. 2.

We are aware that it is not new to apply a fan to a cradle in such manner that the motion of the cradle actuates the fan, as shown, for instance, in Patent No. 34,535, of February 25, 1862; but,

Having thus fully described our invention, we claim—

1. In a platform-cradle, the combination, with the platform and cradle resting thereon, 65 of an upright support secured at its lower end to said platform and carrying at its upper end a horizontal fan-shaft extending over the cradle and provided with a fan, a grooved pulley secured on said fan-shaft near the upright support, and a cord passed around said pulley and having its ends secured to the rocker of the cradle on opposite sides, whereby the rocking of the cradle vibrates the fan, substantially as 70 described.

2. The combination of the platform C, cradle A, and rocker B, upright support D, provided with the loop a, bent portion b, and eye c, horizontal fan-shaft E, carrying the adjustable fan G and provided with the grooved pulley F, double-grooved pulley I, and cord H, 80 passed around said pulleys and connected to the rocker B on opposite sides by the springs g, substantially as described.

ARTHUR DUFFY.
CHARLES J. RELING.
